UNITED STATES PATENT OFFICE.

REGINALD GEORGE ADAMS, OF KALGOORLIE, WESTERN AUSTRALIA, AUSTRALIA.

PLIERS.

1,388,398.

Specification of Letters Patent. Patented Aug. 23, 1921.

Application filed February 19, 1920. Serial No. 359,964.

To all whom it may concern:

Be it known that I, REGINALD G. ADAMS, subject of King of Great Britain, residing at Kalgoorlie, Western Australia, Australia, have invented certain new and useful Improvements in Pliers, of which the following is a specification.

This invention relates to pliers, particularly designed for use by electric wiremen, and an object of the invention is to provide a pair of pliers, by means of which a joint or connection of two wires may be quickly and easily made, eliminating to a material extent, the time absorbing operation of skinning the ends of the wires, which are to be connected in the usual manner, such as by means of a pocket knife.

Another object of this invention, is to provide a pair of pliers as specified, the jaws of which are provided with a plurality of arcuate sharpened portions, graduated in size and decreasing in diameter as they are disposed remote from the axis of the pliers, so that the larger opening for cutting the insulation and pulling it from the larger gage wire is closer to the axis of the pliers, than the opening for stripping the insulation from the smaller gage wire, and also to provide cutting edges between the two larger openings for covering and cutting the conducting wire itself.

A further object of the invention is to provide openings at the outermost ends of the jaws of the pliers for engaging the conductor wires after they have been stripped of insulation to hold them to facilitate the twisting of the wires together to form a secure joint.

Other objects of the invention will appear in the following detailed description taken in connection with the accompanying drawings, forming a part of the specification, and in which drawing:

Figure 1 is a side elevation of the improved pliers.

Fig. 2 is a horizontal enlarged section taken on the line 2—2 of Fig. 1.

Fig. 3 is a detail perspective view of one of the jaws of the pliers.

Fig. 4 is an enlarged section through the pliers showing the jaws thereof in the action of cutting the insulation about an insulated electric conducting wire.

Fig. 5 is a view illustrating a fragment of the jaws of the pliers gripping the meeting

ends of two wires which are to be connected, and

Fig. 6 is a detail view of an ordinary electric conductor illustrating the method of stripping the insulation therefrom. 60

Referring more particularly to the drawings, wherein like characters indicate like and corresponding parts throughout the several views, the jaws 10 and 11 of the pliers are pivotally connected, by means of a pivot pin 12 as is ordinary in the construction of approved types of pliers, and these jaws have handles 13 and 14 connected thereto or formed thereon, and extending upon the opposite side of the pivot pin 12 from the jaws 10 and 11, to permit the manual operation of the jaws.

The facing edges or sides of the jaws 10 and 11 are cut away or recessed from one side, in substantially an egg shape, or oval shape, as clearly shown at 15, in Figs. 1 and 4 of the drawing, and the abutting relatively thin portions of the jaws are each provided with semi-circular openings 16, graduated in size, and gradually decreasing in diameter from the axis or pivot pin 12 of the jaws, as clearly shown in the drawings. The edges of the jaws extending inwardly into the recess 15 at the openings are beveled as shown at 17, forming cutting edges 18, 85

which are adapted to cut through the insulation A of an electric conductor or wire B of approved construction as illustrated in Fig. 4 of the drawings. Positioned intermediate the two largest openings 16 is an oval shaped depression 19, the same being formed by substantially semi-oval depressions formed in each jaw, and this oval shaped depression 19 has its edges sharpened, for cutting the wire or conductor B. 90 The outer ends of the jaws 10 and 11 having their facing surfaces flat, for facial abutment, and these flat surfaces 20 are provided with semi-oval recesses 21, graduated in size to form various sized oval openings when 100 the jaws 10 and 11 are closed as shown in Fig. 1 of the drawings the said openings being provided for gripping the stripped end of wires to facilitate the twisting or connecting of the wires, as indicated in Fig. 5 105 of the drawings.

In forming a joint between the meeting ends of two wires, such as the wires B and C, illustrated in Fig. 5, the insulation A of the wires is cut, at the desired distance from the 110

ends of the wire, and in so cutting, the wire should be placed in the semi-circular recesses 16 the diameter of which is greater than the diameter of the wires B or C so as 5 to insure against the cutting, or rupturing, of the wire, when cutting the insulation, and the outer braiding, or cross covering of the insulation is stripped off by pulling the pliers over the end of the wire, and the wire 10 is then engaged in a smaller set of openings of substantially the same diameter as the wire B and the remainder of the insulation is stripped from the ends of the wires. After the insulation has been stripped from 15 the ends of the wires, they are placed, substantially in parallel relation, and engage in either of the recesses 21, depending upon the size or diameter of the wires, and the jaws 10 and 11 are then brought together, securely 20 clamping the wires therein, after which the ends of the wires are twisted about each other, that is, the ends of the wire C is twisted about the wire D while the end of the wire D is twisted about the wire C, as indicated in 25 Fig. 5, and as is the usual procedure in connecting the meeting ends of two electric conductors. After the wires have been twisted, as shown in Fig. 5 of the drawings, the pliers are released, and the two wires are 30 drawn apart, bringing the convolutions into engagement with each other and forming a secure connection between the wires, which is completed, when it is properly bound or wound with the usual type of adhesive in-

sulating tape employed in making connection with electric conductors. 35

Changes in details may be made without departing from the spirit of this invention, but;

I claim:

1. In pliers, the combination of a pair of pivoted jaws, each of said jaws having a portion cut away upon one side and face, to reduce the thickness thereof through a certain length of its face edge, the reduced 45 faces of said jaws each having a plurality of coöperating semi-circular recesses therein having insulating stripping beveled knife edges graduated in size as they are positioned from the jaw's pivot, the reduced 50 faces of said jaws having coöperating and abutting wire cutting beveled knife edges thereon.

2. In pliers, the combination of a pair of pivoted jaws, each of said jaws having a portion cut away upon one side and face, to reduce the thickness thereof throughout a certain length of its face edge, said reduced thicknesses terminating short of the forward end of said jaws, the reduced faces of said 60 jaws each having a plurality of coöperating semi-circular recesses therein provided with beveled knife edges, and said jaws having coöperating semi-circular depressions in the facing edges thereof upon their forward 65 ends at the place of normal thickness.

REGINALD GEORGE ADAMS.
